BY *J. P. Cornwall* ATT'Y.

UNITED STATES PATENT OFFICE.

CHARLES T. WESTLAKE, OF ST. LOUIS, MISSOURI, ASSIGNOR TO LOCOMOTIVE TENDER FRAME COMPANY, OF ST. LOUIS, MISSOURI, A CORPORATION OF DELAWARE.

LOCOMOTIVE-TENDER UNDERFRAME.

1,370,866.

Specification of Letters Patent.

Patented Mar. 8, 1921.

Application filed October 17, 1919. Serial No. 331,304.

To all whom it may concern:

Be it known that I, CHARLES T. WESTLAKE, a citizen of the United States, residing at St. Louis, Missouri, have invented a certain new and useful Improvement in Locomotive-Tender Underframes, of which the following is a full, clear, and exact description, such as will enable others skilled in the art to which it appertains to make and use the same, reference being had to the accompanying drawings, forming part of this specification.

My invention relates generally to locomotive tenders, and more particularly to a bed or underframe for the tender, the principal objects of my invention being to provide a relatively strong, rigid and substantial underframe; to construct the underframe in a single piece, preferably by casting, thereby greatly simplifying and minimizing the cost of production and providing a construction which eliminates all joints and connections between assembled parts; to form integral with the underframe various brackets and bearings for parts associated with and carried by the underframe; to form body bolsters integral with the underframe and to construct parts of said body bolsters so that they will have ample strength in resisting certain torsional stresses that are produced by the inertia of the truck during buffing and pulling strains.

With the foregoing and other objects in view, my invention consists in certain novel features of construction and arrangement of parts, hereinafter more fully described and claimed, and illustrated in the accompanying drawings, in which—

Figure 1 is a plan view of a tender underframe of my improved construction.

Fig. 2 is a section taken approximately on the line 2—2 of Fig. 1.

Fig. 3 is a side elevational view of the underframe.

Fig. 4 is an enlarged detail section taken approximately on the line 4—4 of Fig. 1.

Fig. 5 is an enlarged detail section taken approximately on the line 5—5 of Fig. 1.

Fig. 6 is an enlarged section taken approximately on the line 6—6 of Fig. 1.

Fig. 7 is an enlarged plan view of a part of one of the side sills of my improved underframe.

Fig. 8 is a cross section taken on the line 8—8 of Fig. 7.

Fig. 9 is an enlarged cross section taken on the line 9—9 of Fig. 1.

As heretofore stated, I propose to form my improved underframe in a single piece, preferably by casting, and as illustrated, said underframe comprises a pair of side sills 10, a front end sill 11, a rear end sill 12, a pair of bolsters 13, and a pair of longitudinal center girders 14, the end portions 15 and 16 of which or those portions between the bolsters 13 and the end sills 12 and 11 being arranged closer together than the main body portions of said girders or those portions between the bolsters. The underframe also includes an integrally formed transversely disposed member 17 disposed at a point substantially midway between the bolsters 13.

The side sills 10 may be of any desired cross sectional shape, although I prefer to make these end sills of I-beam shape with the webs vertically disposed. Likewise the main body portions or those portions of the center girders between the bolsters 13 are of I-beam shape in cross section with their webs vertically disposed. The rear end sill 12 is preferably hollow and of box-like structure, and formed integral with its central portion is a rearwardly projecting buffing member 18. The portions 15 of the center girders are preferably channel-shape in cross section with the webs vertically disposed and the top and bottom flanges outwardly presented, and the space 19 between these end portions is utilized for the draft rigging that is associated with the drawbar positioned at this end of the underframe. In order to accommodate this draft rigging, the members 15 are extended downwardly a short distance below the plane occupied by the lower portions of the main bodies of the center girders 14 and certain lugs and brackets may be formed integral with the inner faces of these members 15, and which lugs or brackets co-operate with parts of the draft rigging.

The portions 16 of the center girders or those portions between the front end sill 11 and adjacent bolster 13 are preferably of I-beam shape in cross section, and formed integral with their forward ends and with the front end sill 11 is a depending housing 20 in which are formed pockets 21 adapted to receive parts of the drawbar and safety

bar which connect the tender underframe with the locomotive underframe.

The end portions of the bolsters 11 or those portions between the side sills 10 and center girders 14 are preferably of I-beam shape in cross section with the webs vertically disposed and the central portions of said bolsters or those portions between the center girders are provided with a pair of vertically disposed webs 23, thereby providing a box-like section. (See Fig. 6).

Formed integral with the webs 23 are top and bottom plates 24 and 25, and which latter, it will be understood are practically continuations of the top and bottom webs on the adjacent portions of the bolsters and the center girders.

Secured in any suitable manner to the central portions of the bottom plates 25 are center bearings 26 which are adapted to cooperate with corresponding bearings on the bolsters of the truck which support the tender frame.

A locomotive tender underframe of my improved construction combines great strength and rigidity with minimum weight, and said underframe can be easily and cheaply produced owing to the fact that it can be readily cast in a single piece and the elimination of joints in the underframe entirely overcomes structural weaknesses which invariably develop where an assembled or fabricated structure is subjected to service strains and vibrations.

While in service and particularly during buffing and pulling strains, the inertia of the trucks produce torsional stresses in the

lower portions of the body bolsters and to counteract and absorb these stresses, the central portions of the bolsters of my improved underframe are reinforced and strengthened by the transversely disposed parallel webs 23, such construction being easily and cheaply produced and very effective in performing the intended functions. 45

It will be readily understood that minor changes in the size, form and construction of the various parts of my improved locomotive tender underframe can be made and substituted for those herein shown and described, without departing from the spirit of my invention, the scope of which is set forth in the appended claims. 50

I claim:

1. A locomotive tender frame cast in a single piece and comprising a pair of flanged side sills, a pair of box-shape end sills, a pair of flanged center girders or sills, and a pair of flanged bolsters, the center portions of which bolsters are box shaped. 60

2. A locomotive tender frame cast in one piece and comprising the following elements which are integrally connected together: a pair of flanged side sills, box shaped end sills, flanged draft and center sills, and flanged bolsters, the central portions of said bolsters being box-shaped and said draft sills having recesses and parts cast integral therewith for the mounting of the draft rigging. 70

In testimony whereof I hereunto affix my signature this 14th day of October, 1919.

CHARLES T. WESTLAKE.
